(57) **CLAIM**

The ornamental design for a support and cable management structure for an electrical device, as shown and described.

DESCRIPTION

FIG. 1 is a top perspective view of a support and cable management structure for an electrical device;

FIG. 2 is a top view thereof;

FIG. 3 is a bottom view thereof;

FIG. 4 is a left side view thereof;

FIG. 5 is a right side view thereof;

FIG. 6 is a back side view thereof; and,

FIG. 7 is a front side view thereof.
